J. W. PEMBERTON,
METHOD OF MOLD MAKING,
APPLICATION FILED OCT. 11, 1915.

JOHN WILMER PEMBERTON, OF LINCOLN, CALIFORNIA.

METHOD OF MOLD-MAKING.

1,183,319.

Specification of Letters Patent. Patented May 16, 1916.

Application filed October 11, 1915. Serial No. 55,276.

To all whom it may concern:

Be it known that I, JOHN WILMER PEMBERTON, a citizen of the United States, and a resident of Lincoln, county of Placer, and State of California, have invented an Improvement in Methods of Mold-Making; and I do hereby declare the following to be a full, clear, and exact description of my invention, such as will enable others skilled in the art to which it appertains to make and use the same.

This invention relates to the method of making, from any substance adapted to "set," such as plaster of Paris, molds to be used in molding into any given form clay, terra-cotta, or other plastic material.

The objects of my invention are to facilitate the construction of the molds; to improve the same; to reduce the cost thereof; and to increase the period of their usefulness.

The molds referred to herein are technically known as "safe-molds," as distinguished from "waste-molds," i. e., molds made in a number of pieces so arranged as to be capable of being withdrawn from the molded structure and of being put together again for a repetition of the molding process.

Prior to my invention, it has been necessary in the terra-cotta, cement block, and other similar industries, first to make a complete model conforming in all respects to the shape and dimensions of the block or structure desired; a mold in plaster of Paris was then made around such model. In my method of making a mold, it is no longer necessary to make such a model, and, by its elimination I effect a gain in time, labor, and materials.

My method of mold-making consists of a series of operations, during the various stages of which the face, sides, and ends of the mold are produced.

In order that my invention may be clearly understood and readily carried into effect, the same is described with reference to the accompanying drawings, in which similar numbers indicate like parts.

Figure 1 is a top view of the adjustable frame. Fig. 2 is a top view of "face" with bars for sides laid thereon. Fig. 3 is a top view of "face" with stops for ends laid thereon and the cast sides in place. Fig. 4 is a cross section on the line "A—A" of Fig.

1, after the frame is filled with plaster of Paris. Fig. 5 is a cross section on the line "B—B" of Fig. 2, after sides are cast. Fig. 6 is a cross section on the line "C—C" of Fig. 3. Fig. 7 is an elevation of the separable end. Fig. 8 is a detailed view in perspective of Fig. 7, the locking device omitted. Figs. 9, 10 and 11 are an elevation, section, and top view, respectively, of the "left" hand supplemental bar. Figs. 12, 13 and 14 are an elevation, section, and top view, respectively, of the "right" hand supplemental bar.

The face of my mold is made as follows: An adjustable frame consisting of four angular strips, 2, is placed on a bench or table-top, 3, in the form of the piece to be made, usually a square or rectangle, one end of each of said strips touching the side of one of the other strips at right angles. The inner edges of the horizontal portion, 4, of the angular strips are beveled, as at 5. The said horizontal portions of said strips are provided with lugs, 6, placed thereon at intervals. One end of three of the said strips is suitably cut away or notched, as at 7, so that the vertical portions, 8, thereof, may contact with each other, overlap the horizontal portions, 4, and form a tight joint. To facilitate the disjoiner and withdrawal of the frame after use, one of said strips is provided with the separable end, 9, likewise notched, as at 7, to form a tight joint. The separable end is held securely in position by the latches, 10. A suitably mounted locking-device with thumb-screws, 11, is provided to lock the frame. Having locked the adjustable strips, I then fill the receptacle formed by the placing of this frame on the table-top, (the table-top acting as a base) with plaster of Paris, or similar substance, and permit the same to "set." I then invert the mass and remove the strips. The plaster of Paris thus cast constitutes the bottom, A, of my mold, that portion of the cast which contacted with the table-top being the "face" of the mold. That portion of the cast which contacted with the bevel, 5, of the said strips forms a chamfer, 12; and that portion of the cast which contacted with the horizontal portion, 4, of the said strips forms a rim, 13, said rim being indented at intervals by reason of contact with the lugs, 6, on said strips. Said chamfer and said rim constitute a seat for the here- 110

inafter described sides and ends of my mold. This completes my first operation in making my mold.

The sides of my mold are made as follows: On top of the "face" and along the edges of the long side thereof, presuming the "face" to be rectangular in form, I then place bars, 14, of suitable shape and of sufficient length to project beyond each end of the "face." Two supplemental bars, a "left" 15, and a "right" 16, are inserted under the bars, 14, to fill the gap between the said bars, 14, and that portion of the "face" indicated at 17. Plaster of Paris is then thrown up by hand against the bars, 14, 15, and 16, the chamfer, 12, and the rim, 13, for the required distance and permitted to "set." I then remove the bars, and the plaster of Paris thus cast constitutes the sides, B, of my mold. Projections on the bottom of the sides formed in the indentations of the rim, 13, constitute joggles for the mold when the sides are put up. This completes my second operation.

The ends of my mold are made as follows: On top of the "face" and along the edges of the short sides thereof, presuming the said "face" to be rectangular in form, I then place suitably shaped stops, 18, of such length that one end of each thereof contacts with the inner surface of one of the previously cast plaster of Paris sides. The other end approaches the inner surface of the opposite plaster of Paris side. I then fill the remaining space with clay, 19, thus continuing the stop to complete the contact with the said opposite plaster of Paris side. Plaster of Paris is then thrown up by hand against the stops, 18, the chamfer, 12, and the rim, 13, for the required distance and permitted to "set." I then remove the said stops, and the plaster of Paris thus cast constitutes the ends, C, of my mold. Projection on the bottom of the ends formed in the indentations of the rim, 13, constitute joggles for the mold when the ends are put up. This completes my third operation.

I thus make a mold consisting of a "face," two sides, and two ends which when assembled comprises a receptacle, the inner convolutions of which constitute the reverse of the molded structure desired. This mold is capable also of being withdrawn from around the molded structure, and it may be used repeatedly in the molding process.

I do not desire to confine myself to the specific form of the bars, 14, 15, and 16, or of the stops, 18, shown in the drawings accompanying this specification, as it is obvious

that bars and stops of different form and 60 appearance may be employed; that the "face" may be smooth or ornamented according to the character of the table-top; that it is immaterial whether the ends or the sides are made first.

Having thus described my invention, what I desire to claim and secure by Letters Patent, is:

1. The method of making a separable mold comprised of a "face," two sides, and two ends, from any substance adapted to "set," for plastic material; said method consisting in first casting in an adjustable frame, suitably maintained, a bottom provided with a "face," then in casting sides 75 for said mold against suitable bars laid on top of said "face" and along two parallel edges thereof, and finally in casting ends for said mold against suitable stops laid on top of said "face" along the other two parallel 80 edges thereof and between the previously cast sides of the mold.

2. The method of making a separable mold for plastic material from any substance adapted to "set"; said method consisting in first casting in an adjustable frame a "face" for said mold; then in casting sides for said mold against the outside of suitable templets laid on top of said "face" and along two parallel edges thereof, and finally in 90 casting ends for said mold against the outside of additional suitable templets laid on top of said "face" along the other two parallel edges thereof and between the previously cast sides of the mold.

3. The method of making a separable mold for plastic material from any substance adapted to "set" without first making a model of the molded structure desired; said method consisting in first casting in an 100 adjustable frame a "face" for said mold, then in casting sides for said mold against the outside of suitable templets laid on top of said "face" and along two parallel edges thereof, and finally in casting ends for said mold against the outside of additional suitable templets laid on top of said "face" along the other two parallel edges thereof and between the previously cast sides of the mold.

In testimony whereof I have hereunto affixed my signature in the presence of two subscribing witnesses.

JOHN WILMER PEMBERTON.
